CLAIM

The ornamental design for a vibrating wand massager, as shown and described.

DESCRIPTION

FIG. 1 is a perspective view of a vibrating wand massager showing my new design;

FIG. 2 is a front view thereof;

FIG. 3 is a back view thereof;

FIG. 4 is right-side view thereof;

FIG. 5 is a left-side view thereof;

FIG. 6 is a side view thereof;

FIG. 7 is a top view thereof;

FIG. 8 is a bottom view thereof; and,

FIG. 9 is an enlarged view of a portion of the body of the invention as indicated in FIG. 2.
